UNITED STATES PATENT OFFICE.

LYMAN E. SMITH, OF MITTINEAGUE, MASSACHUSETTS.

STUFF-REGULATOR FOR PAPER-MACHINES.

SPECIFICATION forming part of Letters Patent No. 394,306, dated December 11, 1888.

Application filed June 11, 1887. Serial No. 241,015. (No model.)

To all whom it may concern:

Be it known that I, LYMAN E. SMITH, of 5
Mittineague, in the county of Hampden and
State of Massachusetts, have invented a new
and Improved Stuff-Regulator for Paper-Ma-
chines, of which the following is a full, clear,
and exact description.

The object of my invention is to provide a
new and improved stuff-regulator for paper-
machines for regulating automatically the
flow of pulp from the pulp-box to the paper-
machine.

The invention consists in the construction
of parts and combinations of the same, as will
15 be fully described hereinafter, and then
pointed out in the claims.

Reference is to be had to the accompanying
drawings, forming a part of this specification,
in which similar letters of reference indicate
20 corresponding parts in all the figures.

Figure 1 is a plan view of my improvement.
Fig. 2 is a sectional side elevation of the same
on the line *x x* of Fig. 1, and Fig. 3 is a vertical
cross-section of the same on the line *y y*
25 of Fig. 2.

The pulp-box A, of suitable size and shape,
is provided with the transverse partition B, ex-
tending from the bottom of the pulp-box up-
ward to within a short distance of the upper
30 open end of the box. The longitudinal par-
tition C extends in the box A between the
partition B and the end of the box A, said
partition reaching from the top to the bot-
tom. The two partitions B and C thus divide
35 the box A into the three compartments D, E,
and F, of which the compartment D is the
pulp-receiver, and is connected near its bot-
tom by the pipe G with the pump for pump-
ing the paper-pulp from the tank into said
40 receiver D. The pulp passing over the trans-
verse partition B into the compartment E is
discharged from the same through the pipe H
upon the paper-machine, and the pulp pass-
ing over the partition B and into the com-
45 partment F is discharged from the same by
the pipe I back into the tank connected with
the pump discharging into the receiver D.

Near the upper edges of the sides of the
box A is arranged a transverse rod, J, on
50 which is adjustably held the gate K, extend-
ing downward in a slightly-inclined position
and resting with its lower end on the upper

inclined edge of the partition B. In the up-
per part of the receiver D is hinged a pan, L,
provided in its rear end with the upwardly- 55
extending rod N, the free end of which passes
over the top of the gate K and through the
forked end of the lever O, pivoted at O' to
the partition P, which is a continuation of the
transverse partition B, being placed between 60
the partition C and the rear side of the pulp-
box A, with which side the said partition is
connected.

The lever O is provided with a rearwardly-
extending part carrying a weight, O², for 65
counterbalancing said lever O. The latter is
also provided with a downwardly-extending
gate, O³, resting against the partition P, and
when the pan is in its lowest position having
its front edge in line with the front edge of 70
said partition P.

The operation is as follows: The pump
forces the paper-pulp through the pipe G into
the receiver D, which is thus filled, so that
the pan L rides on the level of the pulp, and 75
the pulp is discharged over the upper edge of
the partition B into the compartments E and
F, from which part of the pulp passes through
the pipe H upon the paper-machine, and the
surplus pulp in the receptacle F passes 80
through the pipe I back into the tank con-
nected with the pump. The pulp discharged
into the compartment E passes through the
opening formed between the extension-gate
O³ and the gate K, and the latter is set on the 85
rod J to give the required opening necessary
for a certain thickness or weight of paper.
With every stroke of the pump the pulp rises
in the receiver D, raising the pan L with it,
after which the latter settles back again as 90
the pulp flows over the partition B into the
compartments E and F. This up-and-down
motion of the pan L does not affect the lever
O, as the lower prong of the latter rests with
its edge against the bottom of the rod N on 95
account of the counterbalancing-weight O²,
so that the rod N on the up-and-down motion
of the pan L moves between the two forks of
the lever O without affecting the latter. As
soon as the pulp is thick it does not flow very 100
readily over the partition B, and consequently
rises higher in the receiver D, so as to raise
the pan L sufficiently for the rod N to strike
against the upper prong of the forked lever

O, thereby imparting a swinging motion to the lever O, which assumes the position shown in dotted lines in Fig. 3. The extension-gate O³ is thus moved sidewise over the free edge of the partition P, thus diminishing the opening between the partition and the gate K, thereby cutting off the flow of paper-pulp from the receiver D into the compartment E. When the paper-pulp becomes thin, the pan L sinks downward and the rod N presses on the lower prong of the forked lever O, thus again increasing the opening between the gate K and the partition P as the extension-gate O³ swings toward the rear side of the box A. It will thus be seen that a uniform amount of pulp will always flow from the receiver D into the compartment E.

Having thus fully described my invention, I claim as new and desire to secure by Letters 20 Patent—

1. In a stuff-regulator for paper-machines, the combination, with a pulp-box and a pan hinged therein and provided with a projecting rod, of a pivoted and counterbalanced lever, with which the rod of the pan engages, and an extension-gate secured to the said lever and adapted to increase or diminish the opening leading to the discharge-compartment.

ment connected with the paper-machine, substantially as described. 30

2. In a stuff-regulator for paper-machines, the combination, with a pulp-box and a pan hinged in the receiving-compartment thereof and provided with a projecting rod, of a forked and counterbalanced lever, with which the rod of the pan engages, an extension-gate secured to the said lever, and an adjustable gate for regulating the flow of pulp from the receiver into the discharge-compartment, substantially as herein shown and described. 35 40

3. In a stuff-regulator for paper-machines, the combination, with the pulp-box A, provided with partitions forming the receiver D and the discharge-compartments E and F, and the rod J, secured to the sides of said box, of 45 the gate K, held adjustably on said rod, a pan, L, hinged in the receiver D and provided with a rod, N, the lever O, and the extension-gate O³, secured to said lever O and adapted to increase or diminish the opening leading 50 to the discharge-compartment E, substantially as shown and described.

LYMAN E. SMITH.
